(57) **CLAIM**

The ornamental design for a combination food and beverage carrier, as shown and described.

DESCRIPTION

FIG. 1 is a top, front, right side perspective view of a combination food and beverage carrier;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in FIGS. 1-3 and 5-7 illustrate fold lines in the claimed design.

1 Claim, 6 Drawing Sheets

US D785,467 S
